CLAIM

I claim the ornamental design for a stimulation device, as shown and described.

DESCRIPTION

FIG. 1 is a front view of a stimulation device.

FIG. 2 is a right side view of the stimulation device.

FIG. 3 is a left side view of the stimulation device.

FIG. 4 is a rear view of the stimulation device.

FIG. 5 is a bottom view of the stimulation device.

FIG. 6 is a top view of the stimulation device; and,

FIG. 7 is a perspective view of the stimulation device.

The broken lines are directed to environment and are for illustrative purposes only; the broken lines form no part at the claimed design.

1 Claim, 7 Drawing Sheets
